UNITED STATES PATENT OFFICE.

WILLIAM M. KIRCHNER, OF PITTSBURG, PENNSYLVANIA.

DESIGN FOR JELLY-GLASSES.

Specification forming part of Design No. 5,206, dated August 15, 1871.

To all whom it may concern:

Be it known that I, WILLIAM M. KIRCHNER, of Pittsburg, in the county of Allegheny and State of Pennsylvania, have invented a new and Improved Design for a Jelly-Glass; and I do hereby declare the following to be a full, clear, and exact description thereof, reference being had to the accompanying drawings forming part of this specification, which are side views of a jelly-glass made after my improved design.

My design consists of a bowl-shaped jelly-glass. Jelly-glasses of such shape are more convenient as molds than the tumbler-shape heretofore in use, since the jelly can be turned out of the glass of a more perfect shape. They are also more ornamental in appearance. The outer surface of

the bowl may be configurated to relieve the plainness, as, for instance, by making a series of bands, *c*, around it, or by placing any other desired design thereon. Such ornamentation does not form part of my invention.

What I claim as my invention, and desire to secure by Letters Patent, is—

A design for jelly-glasses, as described and shown.

In testimony whereof I, the said WILLIAM M. KIRCHNER, have hereunto set my hand.

WILLIAM M. KIRCHNER.
